DESIGN FOR A CHAIR FRAME

Lawrence M. Michelson, Clayton, Mo., assignor to
Duro Chrome Corporation, St. Louis, Mo., a corporation of Missouri

Application September 4, 1945, Serial No. 121,809

Term of patent 7 years

(Cl. D15—1)

To all whom it may concern:

Be it known that I, Lawrence M. Michelson, a citizen of the United States, residing at Clayton, county of St. Louis, State of Missouri, have invented a new, original, and ornamental Design for a Chair Frame, of which the following is a specification, reference being made to the accompanying drawing, forming a part thereof, in which Figure 1 is a perspective view of the chair

frame; Figure 2 is a front elevational view of the chair frame; Figure 3 is a side elevational view of the chair frame; and Figure 4 is a top plan view of the chair frame embodying my new design.

I claim:

The ornamental design for a chair frame, substantially as shown.

LAWRENCE M. MICHELSON.
